(57) **CLAIM**

The ornamental design for a pump head for a cosmetic container as shown and described.

DESCRIPTION

FIG. 1 is a perspective view of a pump head for a cosmetic container showing my new design;

FIG. 2 is a front view of thereof;

FIG. 3 is a rear view of thereof;

FIG. 4 is a left side view of thereof;

FIG. 5 is a right side view of thereof;

(Continued)

FIG. 6 is a top plan view of thereof;
 FIG. 7 is a bottom plan view of thereof; and,
 FIG. 8 is a perspective view of thereof in an environment of use.
 The broken lines in the figures illustrate portions of the pump head for the cosmetic container that form no part of the claimed design.

1 Claim, 7 Drawing Sheets
